UNITED STATES PATENT OFFICE.

AMANDA A. HALVERSON, OF DELAVAN, MINNESOTA.

LAMP-CHIMNEY HOLDER.

1,289,741.

Specification of Letters Patent.

Patented Dec. 31, 1918.

Application filed February 9, 1918. Serial No. 216,260.

To all whom it may concern:

Be it known that I, AMANDA A. HALVERSON, a citizen of the United States, residing at Delavan, in the county of Faribault, State 5 of Minnesota, have invented certain new and useful Improvements in Lamp-Chimney Holders; and I do hereby declare the following to be a full, clear, and exact description of the invention, such as will enable others skilled in the art to which it appertains to make and use the same.

The invention relates to a lamp chimney holding attachment for lamp burners, and more particularly to the class of lamp chimney holders.

The primary object of the invention is the provision of a holder of this character wherein the construction thereof permits the detachable engagement of the same with 20 the chimney retaining arms of a lamp burner, so that the chimney will be held securely in place upon the burner, without the possibility of accidental tilting of the same or the falling of the chimney from said burner.

Another object of the invention is the provision of a holder of this character wherein auxiliary clamping members or cheeks will engage the neck of the chimney 30 when mounted in the burner and engaged by the resilient arms or fingers upstanding from the base of the burner, so that there is no possibility of the lamp chimney becoming accidentally detached from the burner, and the said chimney will be permitted to 35 expand and contract without the possibility of the breakage thereof resultant from the binding action of the holder when carried by the burner.

A further object of the invention is the provision of a holder of this character, which can be readily mounted upon the lamp burner and detached therefrom and also will permit the placing of the chimney 45 in position upon the burner or its removal therefrom.

A still further object of the invention is the provision of a holder of this character wherein the clamping action of the resilient 50 fingers on the lamp burner is augmented so as to securely retain the lamp chimney in place thereon and to avoid the accidental working loose of the lamp chimney when in position upon the burner.

A still further object of the invention is the provision of a holder of this character

which is extremely simple in construction, thoroughly reliable and efficient in its purpose, strong, durable and inexpensive to manufacture and install.

With these and other objects in view, the invention consists in the features of construction, combination and arrangement of parts as will be hereinafter fully described, illustrated in the accompanying drawing 65 and pointed out in the claims hereunto appended.

In the accompanying drawing:

Figure 1 is a side elevation of the lamp burner showing a chimney held in place 70 thereon by the holder constructed in accordance with the invention.

Fig. 2 is a sectional view on the line 2—2 of Fig. 1 looking in the direction of the arrows,

Fig. 3 is a perspective view of the holder detached.

Similar reference characters indicate corresponding parts throughout the several views in the drawing.

Referring to the drawing in detail, A designates generally the burner, which as usual is formed with the circular shaped base 5 having rising therefrom at its peripheral edge a plurality of resilient fingers or 85 arms 6, which slightly converge upwardly and have their upper ends inwardly curved as at 7 for positive frictional engagement with the neck 8 of a lamp chimney 9 which is of the ordinary well known construction. 90 The fingers or arms 6 are spaced the desired distance apart, as usual and serve to retain the lamp chimney 9 in place upon the lamp burner in the ordinary well known manner.

The lamp chimney holder comprises a plurality of comparatively short coiled convoluted retractile springs 10 and located between the adjacent ends of these springs are clamping plates 11 constituting gripping cheeks, the plates being preferably outwardly bowed to a slight degree to assure positive gripping action on the neck of the chimney 9 in a manner hereinafter fully described.

Each plate 11 is preferably of rectangular 105 shape and is formed at its opposite longer edges with opposed ears 12, which are folded on themselves to provide eyes 13 in which are loosely engaged the terminal coils of convolutions of adjacent springs 10 and in 110 this manner plates and springs are loosely connected to each other.

The ears 12 on each plate 11 are located nearer one end thereof than the other, so that one end portion at one side of the ears 12 is longer than the other end portion at 5 the opposite side thereof and these longer end portions of the plates 11 are disposed downwardly in the direction of the base 5 of the burner A when the holder is applied thereto for securely retaining the lamp 10 chimney 9 in place upon the burner.

The ears 12 on the plates 11 at their extremities overlap each other so as to close the eyes 13 to prevent the accidental disengagement of the terminal convolutions of 15 coils of the springs 10 from the plates 11 in the use of the lamp chimney holder.

In the application of the lamp chimney holder the springs at the intermediate points thereof are engaged over the fingers or arms 20 6 on the burner A so that the plates 11 are disposed between the fingers or arms 6, preferably at a medial point therebetween to engage with the neck 8 of the lamp chimney 9 at points independent of the engagement of 25 the fingers or arms 6 therewith. The springs 10 and plates 11 are disposed concentrically of the neck 8 of the lamp chimney 9 and the resiliency of said springs 10 acts upon the plates 11 to force the same into positive 30 gripping engagement with the neck 8 of the lamp chimney and thereby augmenting the gripping action of the fingers or arms 6 on the burner A upon the said neck 8 of the lamp chimney, so as to firmly and positively 35 hold the lamp chimney in place in the burner, to avoid any possibility of the lamp chimney falling from the burner or working loose therefrom, yet the lamp chimney can be readily inserted in place in the burner or removed therefrom as the occasion may require.

The springs 10 are of the proper resiliency so as to avoid any undue binding action upon the neck of the chimney 9 to eliminate 45 the breaking of the chimney due to expansion and contraction thereof, although the said chimney will be firmly held in place upon the burner A and can be readily inserted between the fingers or arms 6 upon the latter and detached at the will of the user.

Copies of this patent may be obtained for five cents each, by addressing the "Commissioner of Patents, Washington, D. C."

Each of the plates 11 which are normally outwardly bowed are made from suitable resilient material, such as metal, having the required resiliency to exert a pressure against the neck 8 of the lamp chimney 9 to 55 coact with the springs 10 for the firm and positive gripping of the lamp chimney to hold the same upon the burner.

From the foregoing it is thought that the construction and manner of use of the lamp chimney holder will be clearly understood and therefore a more extended explanation has been omitted. However it is contemplated within the scope of the invention to make changes, variations and modifications 65 such as come properly within the scope of the appended claims, without departing from the spirit of the invention or sacrificing any of its advantages.

What is claimed is:—

1. A lamp chimney holder of the character described comprising resilient means for encircling a lamp chimney, and plates carried on the resilient means at intervals thereof loosely connected thereto with portions of 75 each plate projected above and below the resilient means.

2. A holder of the character described comprising a plurality of coils or tractile springs, outwardly bowed plates arranged between the adjacent ends of the springs, and ears formed on opposite sides of the plates and engaged with the terminal coils of said springs for loosely connecting the 80 latter and the plates together.

3. A lamp chimney holder of the character described comprising a plurality of coil resilient members, a plurality of plates, each arranged between the adjacent ends of the resilient members, and ears at opposite sides 85 of the plates and bent on themselves to form eyes loosely connected to the terminals of the resilient members.

In testimony whereof, I affix my signature, in the presence of two witnesses.

AMANDA A. HALVERSON.
